(57) **CLAIM**

The ornamental design for a lid for a disposable cup, as shown and described.

DESCRIPTION

FIG. 1 is an elevation view of the right side of a lid for a disposable cup that has the design.

FIG. 2 is an elevation view of the front of the lid for a disposable cup.

FIG. 3 is an elevation view of the back.

FIG. 4 is a top plan view.

FIG. 5 is a bottom plan view.

FIG. 6 is an elevation view of the left side.

FIG. 7 is a back, top, and left side perspective view of the lid for a disposable cup.

FIG. 8 is an elevation view of the front of another lid for a disposable cup that has the design.

FIG. 9 is an elevation view of the back of the lid for a disposable cup.

FIG. 10 is an elevation view of the right side.

FIG. 11 is an elevation view of the left side.

FIG. 12 is a bottom plan view.

FIG. 13 is a top plan view; and,

FIG. 14 is a back, top, and left side perspective view.

The broken lines represent elements of the lid for a disposable cup that form no part of the claimed design.
